ATTORNEY

UNITED STATES PATENT OFFICE.

ALBERT W. FURNESS, OF CHESTERTON, INDIANA.

CURRENT-DEFLECTOR FOR MARINE VESSELS.

1,258,554.

Specification of Letters Patent.

Patented Mar. 5, 1918.

Application filed April 13, 1917. Serial No. 161,889.

To all whom it may concern:

Be it known that I, ALBERT W. FURNESS, a citizen of the United States, residing at Chesterton, in the county of Porter and 5 State of Indiana, have invented new and useful Improvements in Current-Deflectors for Marine Vessels, of which the following is a specification.

The present invention relates to improvements in means for facilitating the travel of 10 bodies, such as vessels, torpedoes, etc., in the water.

In carrying out my invention it is my purpose to arrange on the bow of a marine 15 vessel, a torpedo or the like, a nose member so constructed and arranged as to provide a deflector for the currents of water through which the body travels, to have a cutting effect upon the water through which the 20 body travels and to direct the said water through the nose member to the opposite sides of the bow of the body, consequently reducing the force of obstruction by the water and assisting in materially increasing 25 the speed of the body or vessel.

It is a further object of the invention to produce a deflector which may be formed with a vessel in the construction thereof or 30 which may comprise a separable member that may be easily attached to or detached from the vessel.

It is a still further object of the invention to produce a device of this character which shall embody the desirable features of simplicity, cheapness and efficiency.

With the above and other objects in view the improvement resides in the construction, combination and arrangement of parts set forth in the following specification and falling 40 within the scope of the appended claims.

In the drawings:

Figure 1 is a perspective view of a portion of the bow of a marine vessel provided with the improvement,

45 Fig. 2 is a horizontal sectional view approximately on the line 2—2 of Fig. 1.

Fig. 3 is a vertical transverse sectional view approximately on the line 3—3 of Fig. 1,

50 Fig. 4 is a side elevation of the bow of a submarine vessel or torpedo provided with the improvement.

Fig. 5 is a horizontal sectional view approximately on the line 5—5 of Fig. 4,

55 Fig. 6 is a vertical transverse sectional

view approximately on the line 6—6 of Fig. 4,

Fig. 7 is a top plan view illustrating a modification,

Fig. 8 is a side elevation of the same, and 60

Fig. 9 is a sectional view approximately on the line 9—9 of Fig. 7.

The improvement is designed for use upon all classes of marine vessels, torpedoes or the like, and in the drawings, and referring 65 particularly to Figs. 1 to 3 thereof, the numeral 1 designates the bow of a vessel of any ordinary construction having my improvement applied thereto.

The nature of the improvement is such as 70 to render the same subject to modifications as to shape, size, etc., to accord with the class of vessel or other object upon which it is applied, and the improvement may be made as part of a vessel in the construction of such 75 vessel or may be in the nature of a separable element that may be applied to the vessel after the construction of said vessel. When the improvement is employed upon com-

paratively small craft or objects, the same 80 is secured to the top and bottom thereof, the lower portion of the improvement being in a line with or above the keel of the vessel and the upper portion being above the water line of the vessel. The improvement is pref- 85

erably constructed of metal but, of course, may be constructed of any other desired material so treated as to render the same not liable to disintegration from the influence 90 of the water, and, of course, of sufficient strength and rigidity to withstand the strain to which it is subjected. In the referred to

Figs. 1 to 3 of the drawings the nose or deflector member includes a bottom plate 2, a top plate 4 and angular side members 3 95 formed integrally with the top and bottom plates. The top plate 4 may be provided with a central slot or opening surrounded by an upstanding flange 4' and this flange

engages with the opposite sides of the bow 100 of the vessel 1 and is secured thereto, as

clearly illustrated in Fig. 1 of the drawings, while the bottom plate 2 may be arranged in a line with the keel of the vessel 1 and be riveted or otherwise secured thereto. The 105 angular sides 3 are disposed a suitable distance from the sides 5 of the vessel 1 providing a passage between the inner surfaces of the said sides 3 and the sides of the vessel. By reference to Fig. 2 of the drawings it 110

will be noted that the outer end or mouth of the nose or deflector is of a comparatively great width with respect to the bow of the vessel 1, while the ports or passages provided 5 between the angular sides 3 of the improvement and the angular sides 5 of the vessel are of a width more than one-half of the width of the intake or mouth of the deflector. By such construction it will be 10 noted that a comparatively large volume of water is permitted to enter the deflector through the mouth thereof while the water gradually decreases in volume when passing through the ports A—A at the discharge 15 end of the deflector, when the vessel plows through the water, so that the currents of water are thus deflected away from the sides of the bow of the vessel and as a consequence the volume or force of volume of water contacted by the bow of the vessel is materially 20 decreased, and hence the propelling power of the vessel is materially increased.

To regulate the flow of water through the passages A—A, I hingedly secure, as at B, 25 to the inner surface of each of the angular sides 3 of the deflector, a gate valve C, the same being controlled by flexible elements D passing over suitable pulleys E, which 30 flexible elements D may be connected with any suitable operating mechanism upon the deck of the vessel.

In Figs. 4 to 6 a nose or deflector is illustrated which is applicable to the conical bows of submarine vessels, torpedoes or similar devices. In the said figures of the drawings, the numeral 7 designates the cone-shaped bow of a submarine vessel or torpedo, and in this instance the deflector 6 is round in cross section but is of a substantially 40 low frusto-conical construction, the said body gradually increasing the width from the intake or mouth of the same to its opposite end, and its widened end is provided upon its top and bottom with centrally extending members or ears 8 and 9 respectively 45 which are secured in any desired or preferred manner to the top and to the bottom of the vessel or torpedo 7. The widened end of the deflector 6 is rounded inwardly from the members 8 and 9, as clearly illustrated in Figs. 4 and 5 of the drawings, and this construction has the same cutting effect upon 50

the water as the device disclosed in Figs. 1, 2 and 3 and also the same effect of directing the water through the passages F—F between the widened ends of the deflector and the angular sides of the bow of the vessel or torpedo 7.

In the remaining figures of the drawings, the bow of the vessel 12 has extending outwardly therefrom a deflector comprising angularly disposed side plates 13—13 that are connected at their outer ends by transverse brace members 14, the inner ends of the said plates being provided with straps 15 that are secured in any desired manner to the opposite sides of the bow of the vessel 12. Angularly disposed brace members 16 connect with the outer brace member 14 and with the straps 15, while a substantially V-shaped brace member 17 is secured, as at 18, to the bow of the vessel 12 and is likewise secured, as at 19, to the inner sides of the plates 13.

Having thus described the invention, what I claim is:

1. In a marine vessel, a deflector secured at the bow thereof and comprising a hollow member having angular sides terminating adjacent to the sides of the vessel at the bow of the vessel, valves controlling the passages between the inner sides of the deflector and the sides of the vessel, and actuating means for said valves.

2. A deflector for marine vessels including plates arranged angularly at the bow of a vessel, providing a water intake at the outer end of the plates and providing passages between the sides of the bow of the vessel and the said plates, said passages being of a width more than one-half the distance between the plates at the outer ends thereof.

3. A deflector for marine vessels including plates arranged angularly at the bow of a vessel, providing a water intake at the outer end of the plates and providing passages between the sides of the bow of the vessel and the said plates, said passages being of a width more than one-half the distance between the plates at the outer ends thereof, gate valves in said passages, and regulating means for said valves.

In testimony whereof I affix my signature
ALBERT W. FURNESS
